UNITED STATES PATENT OFFICE.

DAVID BRANDFON, OF BROOKLYN, NEW YORK.

EYEGLASS CLEANER AND POLISHER.

Application filed July 2, 1928. Serial No. 289,886.

This invention relates to an improved eyeglass cleaner and polisher.

An object of the invention is to provide a device of this character having bulged pockets for the reception of the thumb and finger of the hand so as to press said pockets against opposite surfaces of an eyeglass or other analogous article and permit the desired pressure and manipulation for cleaning and polishing purposes.

A further object is to provide a device of this character in which the pockets are supported on arms pivotally connected by a link, the latter being so arranged as to hold the free ends of the arm apart and prevent any possibility of said arms or other frame structure from contact either with the glass or frame of the glass and allow only the flexible pockets to contact therewith.

20 A further object is to provide a device of the character stated in which said pockets are of chamois or any other suitable flexible material having sufficient slack or freedom to allow a proper manipulation thereof to thoroughly clean the entire surface of the glass.

With these and other objects in view, the invention consists in certain novel features of construction and combinations and arrangements of parts, which will be more fully hereinafter described and pointed out in the claims.

In the accompanying drawings—

Figure 1 is a view in longitudinal section illustrating my improved device in operative position in the act of cleaning or polishing an eyeglass;

Figure 2 is a perspective view of my improved device in operative position;

40 Figure 3 is a perspective view of my device in reversed or inoperative position so as to occupy as small a space as possible.

1 and 2 represent rods or arms which are pivotally connected at one end by my improved link 3. This link 3 is in the form of a plate having its ends located in bifurcated portions of the arms 1 and 2 and pivotally connected to said arms by rivets or other form of pivot 4.

50 The link 3 has a projection or enlargement 5 thereon which is adapted to be engaged by the arms 1 and 2 and limit the pivotal movement of said arms toward each other so as to hold the free ends of the arms

spaced apart for a reason that will more 55 fully hereinafter appear.

The arms 1 and 2 at their free ends are made with rings 6 which may constitute integral parts of the arms, and on these rings 6 flexible cleaning and polishing material 7 60 is secured by means of clamping rings 8 over which the edges of the material 7 are folded.

This flexible material 7 is bulged and has a sufficient slack therein so as to form what I refer to as pockets, as these parts constitute pockets for receiving the thumb and finger of the hand, and they also function as cleaning and polishing devices to engage the opposite sides of a glass 9 which may constitute part of an eyeglass or spectacle, and I 70 have illustrated a frame 10 on the glass 9 although of course the device may function to clean a glass which has no frame.

An important feature of my invention is the fact that I provide a flexible cleaning 75 and polishing material on each of the arms which has a sufficient bulge or slackness to form finger and thumb receiving pockets, so that the material may be pressed as tightly as desired against the glass without any 80 possibility of any portion of the frame of the device engaging the frame or glass of the spectacles or eyeglass.

While I have illustrated a particular manner of securing these so-called pockets to the 85 rings 6 of the arms 1 and 2, it is altogether possible that this manner of securing may be changed to suit conditions.

When the device is not in use, the arms 1 and 2 may be swung to the position shown 90 in Figure 3 so that the two members of the device may lie close together and occupy but little space in a hand bag or pocket.

Various changes and alterations might be made in the general form of the parts, described without departing from my invention, and hence I do not limit myself to the precise details set forth but consider myself at liberty to make such changes and alterations as fairly fall within the spirit and 100 scope of the appended claims.

I claim:

1. An eyeglass cleaner and polisher, comprising a pair of arms, means pivotally connected with said arms and spacing them 105 apart, means limiting the movement of the free ends of the arms toward each other, and flexible finger and thumb receiving

pockets at the free ends of said arms adapted to engage the opposite sides of the article to be cleaned and polished.

2. A device of the character described, including a pair of arms, a link pivotally connecting the arms at one end, an enlargement on the link adapted to be engaged by the arms to limit the movement of the free ends

of said arms toward each other, rings on the free ends of the arms, and flexible pockets 10 clamped on said rings and bulged inwardly toward each other.

Signed at Brooklyn, in the county of Kings and State of New York, this 29th day of June, A. D. 1928.

DAVID BRANDFON.
